CLAIM

The ornamental design for a lamp, as shown and described.

DESCRIPTION

FIG. 1 is a front elevational view of a lamp showing the new design;

FIG. 2 is a rear elevational view thereof;

FIG. 3 is a left-side elevational view thereof;

FIG. 4 is a right-side elevational view thereof;

FIG. 5 is a top plan view thereof;

FIG. 6 is a bottom plan view thereof;

FIG. 7 is a front, bottom, left perspective view thereof; and,

FIG. 8 is a rear, bottom, right perspective view thereof.

(Continued)

The broken lines shown in the drawings illustrate portions of the lamp that form no part of the claimed design.

1 Claim, 8 Drawing Sheets
